UNITED STATES PATENT OFFICE.

GEORGE M. HALLENBECK, OF WALLINGFORD, CONNECTICUT, ASSIGNOR TO
THE SIMEON L. & GEORGE H. ROGERS COMPANY, OF WALLINGFORD,
CONNECTICUT, A CORPORATION.

DESIGN FOR A HANDLE FOR SPOONS, FORKS, OR SIMILAR ARTICLES.

No. 38,583.

Specification for Design.

Patented April 23, 1907.

Application filed March 25, 1907. Serial No. 364,550. Term of patent 7 years.

To all whom it may concern:

Be it known that I, GEORGE M. HALLENBECK, a citizen of the United States, residing at Wallingford, in the county of New Haven and State of Connecticut, have invented a new, original, and ornamental Design for a Handle for a Spoon, Fork, or Similar Article; and I do hereby declare the accompanying drawing to be a full, clear, and exact illustration of the same, and which said drawing

constitutes part of this specification, and represents a face view of a handle for a spoon, fork, or similar article embodying my design.

Claim.

The ornamental design for a handle for a spoon, fork or similar article, as shown.

GEORGE M. HALLENBECK.
